UNITED STATES PATENT OFFICE.

GEORGE L. REYNOLDS, OF AUBURN, NEW YORK.

HORSESHOE.

No. 866,733.

Specification of Letters Patent.

Patented Sept. 24, 1907.

Application filed October 13, 1906. Serial No. 338,705.

To all whom it may concern:

Be it known that I, GEORGE L. REYNOLDS, a citizen of the United States, and a resident of the city of Auburn, in the county of Cayuga and State of New York, have invented a new and Improved Horseshoe, of which the following is a specification.

My invention relates to horse shoes which may be secured in position without the use of nails, and the object of my improvement is—to provide a shoe which 10 can be securely attached to the hoof by means of connections that will project the least possible distance from the surface of the hoof; and that when so attached, may be easily detached and which will not interfere with the proper natural expansion and growth of the 15 hoof.

My invention consists of a main portion or shoe proper, toe and side pieces, springs secured in depressions in the upper surface of the shoe, and the hooks or claws engaged to the outer ends of the springs and 20 adapted to engage in slots cut into the outer surface of the hoof for the purpose of securing the shoe to the hoof.

The invention is illustrated in the accompanying drawings, of which

25 Figure 1 is a plan of the shoe and fastening devices. Fig. 2 is a cross section on the line A—A of Fig. 1. Fig. 3 is a perspective view of one of the springs. Fig. 4 is a cross section on the line B—B in Fig. 1. Fig. 5 is a similar cross section showing a modified form of 30 spring shank.

Similar reference characters refer to like parts throughout the several views.

In the drawings, the body of the shoe 1, is provided with a toe calk 2 and heel calks 3. Projecting from the 35 upper side are toe pieces 4, and side pieces 5 which are adapted to fit small grooves cut into the lower edge of the horn of the hoof to prevent the shoe from slipping laterally on the hoof. The upper surface of the shoe is formed with depressions in which are seated the front 40 spring 6 and the side springs 7. When the shoe is formed, which may be either by drop-forging or molding, pins 8 are formed in these depressions in the shoe. The springs are provided with counter-sunk apertures 45 through which these pins 8 are adapted to extend, when the springs are in proper position. The pins are riveted down, thus preventing any movement of the springs at those points. As will be seen in Fig. 3, the free ends of the arms of the springs are provided with small ridges 50. Because of this construction, when the pins are headed down tightly to position, the springs will be under considerable tension. The springs are provided

at the outer ends with downwardly projecting shoulders or ribs 10, which are engaged by the hooks or claws 11, as shown in Fig. 2.

To secure the shoe to the hoof, the hooks 11 are put 55 in position, the shoe placed against the bottom of the hoof and grooves cut into the horn of the hoof. The lower ends of the hooks 11, and with them the down-turned portions 10 of the springs 6 and 7, are raised by means of any desirable tool being pushed in beneath 60 the lower end of the hooks 11 into the opening 12. The outer ends of the springs being raised in this manner, the upper ends of the hooks 11 will engage in the slots 65 cut in the horn of the hoof for their reception. The resilience of the spring will hold the shoe against the hoof as soon as all three hooks 11 properly engage in their respective slots. The downward pull of the hook 11 caused by the resilience of the spring 6 is more than equal to the entire holding power of the usual eight 70 nails now employed to secure a shoe to a horse's hoof. The positions of the rear hooks 11 are such that they will exert their power far to the rear of where nails can be driven. This gives a great gain in leverage and permits the shoe being held more securely than by the use of nails. In Fig. 5, a modified manner for fastening 75 the end of the spring is shown. The sides of the spring 16 are beveled and the material of the shoe 17 immediately adjacent to the spring is swaged down over the beveled portion, and thus secures it firmly in position. Any other desirable manner of securing the springs 6 80 in position, may be employed. The advantage of this construction appears more clearly when it is considered that nails are usually driven so as to separate the longitudinal fibers of the horn of the hoof and therefore must be clenched to keep them from pulling out. 85 With my improved construction, a large base area is taken advantage of and the tension of the springs insures a permanent connection between the hoof and the shoe. To remove the shoe, it is only necessary to lift up the outer ends of the springs and their hooks 11 90 so as to disengage the hooks from the hoof.

Having now explained my improvement, what I claim as my invention and desire to secure by Letters Patent is,—

1. A horse shoe formed with recesses, springs secured 95 in these recesses, and hooks in engagement with these springs, which hooks are adapted to secure the shoe to the hoof of a horse.
2. A horse shoe formed with recesses, springs having 100 their ends fastened in these recesses and provided with downwardly projecting hooks at their middle portions, and claws adapted to engage grooves in the hoof of the horse and carried by these downward projecting hooks on the springs.

3. A horse shoe formed with sets of grooves, springs fitting in said grooves, and having their ends secured to said shoe, claws in engagement with the middle portions of said springs and adapted to secure the shoe to the hoof
5 of a horse, said springs being formed with a ridge at the lower side of each end.
4. A horse shoe formed with toe and side pieces to prevent the shoe moving laterally when secured to the hoof, springs secured to said shoe, and hooks in engage-

ment with the springs, which hooks are adapted to secure 10 the shoe to the hoof.

In testimony whereof I have signed my name in the presence of two subscribing witnesses.

G. L. REYNOLDS.
